(57) **CLAIM**

The ornamental design for a powered wagon with hopper, as shown and described.

DESCRIPTION

FIG. 1 is a front perspective view of a powered wagon with hopper showing our new design;

FIG. 2 is a rear perspective view of the powered wagon with hopper thereof;

FIG. 3 is a front elevational view of the powered wagon with hopper thereof;

FIG. 4 is a right elevational view of the powered wagon with hopper thereof;

FIG. 5 is a rear elevational view of the powered wagon with hopper thereof;

FIG. 6 is a left elevational view of the powered wagon with hopper thereof; and,

FIG. 7 is a top elevational view of the powered wagon with hopper thereof.

The broken lines showing in the figures are for the purpose of illustrating environment and form no part of the claimed design.
